UNITED STATES PATENT OFFICE.

FRANK G. RUDDIMAN, OF MUSKEGON, MICHIGAN.

RUNNING-BOARD MAT.

1,137,354.

Specification of Letters Patent. Patented Apr. 27, 1915.

Application filed May 27, 1914. Serial No. 841,187

To all whom it may concern:

Be it known that I, FRANK G. RUDDIMAN, a citizen of the United States, residing at Muskegon, in the county of Muskegon and State of Michigan, have invented a certain new and useful Improvement in Running-Board Mats, of which the following is a full, clear, concise, and exact description, reference being had to the accompanying drawings, forming a part of this specification.

My invention relates to mats, particularly that class of mats formed by weaving cocoa yarn, and the object of my invention is to provide a mat of this class that may be mounted and retained upon the running-board of an automobile or other vehicle.

The specific embodiment of my invention hereinafter described and subsequently claimed comprises retaining devices in the form of wire springs interwoven with the yarn and constituting therewith a unitary structure. By weaving the retaining springs into the yarn of the mat as aforesaid, I am enabled to produce a neat-appearing running-board mat that may be cheaply manufactured, inasmuch as no extra fastening devices are required to fix the retaining springs with respect to the woven cocoa yarn. The retaining springs before-mentioned are so shaped and disposed that they serve to effectively clamp the woven yarn to an associated running-board, the springs being practically out of sight when the mat is in position upon the running-board.

In the accompanying drawings illustrating my invention—Figure 1 is a perspective view of the running-board mat of my invention, this view showing clearly the retaining springs which are woven into the yarn of the mat; Fig. 2 is an elevational view illustrating my improved mat in position upon the running-board of an automobile; Fig. 3 is a transverse sectional view illustrating how the retaining springs are interwoven with the yarn of the mat, and Fig. 4 is a fragmentary sectional view taken on the line 4—4 of Fig. 3.

As illustrated in the drawings, the running-board mat of my invention comprises a pair of retaining springs A, A, arranged to retain the mat of woven yarn upon the running-board B of an automobile or other vehicle. The springs A, A, may be said to be substantially U-shaped, inasmuch as each of said springs consists of a single piece of

spring wire bent back upon itself to the shape most clearly shown in Figs. 1 and 3. When the running-board mat is in position upon the running-board of an automobile, 60 the springs A, A assume conformations more like a perfect U. The lowermost one of the arms of each of the springs A, A is so shaped that it will most effectually grip the under side of the running-board with which the mat is associated. As will be presently pointed out, the springs A, A are interwoven with the yarn of the mat, and constitute therewith a unitary structure.

As is most clearly illustrated in Figs. 3 70 and 4 of the drawings, the mat of my invention comprises a plurality of strands C of cocoa yarn, these strands being known in weaving parlance as the "warp." Interwoven with the strands or warp C are the 75 plugs D of cocoa yarn which, when the mat is completed, have a substantially U-shape with their ends projecting upwardly to form the tufts upon which the person entering the automobile or other vehicle with 80 which the mat is associated may wipe his shoes. Interposed between each row of plugs D, as is most clearly illustrated in Fig. 4, is a filler of cocoa yarn E. The warp plugs and fillers are woven together, 85 as is illustrated in Figs. 3 and 4, upon a hand loom or suitable mat-weaving machine, and the resulting rectangular block of woven yarn is bound with a suitable braid of cocoa yarn sewed in position, as is clearly 90 shown in Fig. 3, this braid being indicated at F. As is clearly illustrated in Figs. 3 and 4, the retaining springs A are interwoven with the warp, plugs and fillers of the mat and are thus retained in operative position 95 without employing any extra securing devices for this purpose. The springs A, A are positioned when the mat is being woven and can not be removed after the mat has been completed, due to the offset portions 100 G, G of the springs which abut against the adjacent edges of the mat.

The springs A, A may be made of any suitable wire. Inasmuch as the upper arm of each of the springs is embedded in the 105 woven yarn, and inasmuch as the lower arm of each of the springs lies under the running-board when the mat is in position, the springs are practically out of sight. Although one spring would perhaps suffice to 110 retain the woven yarn structure upon the running-board, I find it desirable to utilize

a plurality of springs, inasmuch as when the mat is used there is a tendency to throw it from position upon the running-board.

Having thus described my invention, what I claim as new and desire to secure by Letters Patent is:—

1. A running-board mat comprising, in combination, interwoven strands, fillers and plugs, and a substantially U-shaped spring having one arm thereof interwoven with said strands, fillers and plugs, and the other arm extending transversely of the mat on the under side thereof, said strands, fillers, plugs and spring being thus carried together and constituting a unitary mat structure.
2. A running-board mat comprising, in combination, interwoven strands, fillers and plugs, and a running-board engaging spring having a portion thereof interwoven with said strands, fillers and plugs, said strands, fillers, plugs and spring being thus carried

together and constituting a unitary mat structure.

3. A running-board mat comprising, in combination, woven yarn and a running-board engaging spring interwoven with the yarn and with the yarn constituting a unitary mat structure.

4. A running-board mat comprising, in combination, woven yarn and a substantially U-shaped running-board engaging spring having one arm thereof interwoven with the yarn and the other arm extending under the woven yarn, said spring adapted to clamp the woven yarn to a running-board, said yarn and spring being thus carried together and constituting a unitary mat structure.

In witness whereof, I hereunto subscribe my name this 14th day of May, A. D. 1914. 40

FRANK G. RUDDIMAN.
